UNITED STATES PATENT OFFICE.

ALBERT DAVOUST, OF BOSTON, MASSACHUSETTS.

AUTOMATIC PENCIL.

Application filed October 8, 1924. Serial No. 741,379.

To all whom it may concern:

Be it known that I, ALBERT DAVOUST, a citizen of the Republic of France, and a resident of Boston, in the county of Suffolk 5 and State of Massachusetts, have invented a new and useful Improvement in Automatic Pencils, of which the following is a specification.

My invention relates to automatic pencils, 10 and its object, generally speaking, is to improve and simplify the construction of pencils of this type in the manner herein-after more fully set forth.

Specific objects of my invention are to 15 provide an automatic pencil in which leads of different grades or colors may be placed in the pencil point from a rotatable magazine, and replaced in said magazine when it is desired to use a lead of different grade 20 or color; and to provide a simple means for feeding the lead through the pencil point.

With the foregoing objects in view my invention comprises as its essential features a barrel having a transverse slot, a point secured to one end of said barrel and having an axial bore communicating with said slot, a cap engaging the other end of said pencil, a magazine rotatably mounted in said barrel, an interiorly threaded sleeve rotatably 25 mounted on said valve, and a pusher-rod provided with a rack adapted to engage the threads on the interior surface of the sleeve, together with means for holding the said pusher-rod in inoperative position and releasing it to operative position.

An illustrative embodiment of my invention is shown in the drawings which accompany and form a part of this specification in which—

40 Figure 1 is a longitudinal vertical section taken on the line 1—1 of Fig. 2;

Fig. 2 is a similar section taken on the line 2—2 of Fig. 1;

45 Fig. 3 is a longitudinal vertical section of the interiorly threaded sleeve rotatably mounted on the barrel;

Fig. 4 is a transverse section taken on the line 4—4 of Fig. 3;

50 Fig. 5 is a transverse section taken on the line 5—5 of Fig. 2;

Fig. 6 is a transverse section taken on the line 6—6 of Fig. 2;

Fig. 7 is a transverse section taken on the line 7—7 of Fig. 2;

55 Fig. 8 is a transverse section taken on the line 8—8 of Fig. 2;

Fig. 9 is the front elevation of the pusher-rod;

Fig. 10 is a side elevation of said pusher-rod.

In the particular drawings selected for more fully disclosing my invention 20 is a barrel provided with a transverse slot 21 extending from a point near the upper end of the barrel to a point near the lower end thereof, and provided at its lower end with an axial bore 22 communicating with the bore 23 arranged axially in the point 24 which has threaded engagement with the lower end of said barrel. Rotatably mounted on the reduced lower part 25 of the barrel is an interiorly threaded sleeve 26 confined between the point 24 and the larger upper portion of said barrel.

The slot 21 extends transversely through the reduced end portion of the barrel as indicated in Fig. 8. Rotatably mounted in the enlarged upper portion of the barrel is a lead magazine 26 herein shown as having five compartments for leads of different colors or different grades, said magazine being provided with a head 27 herein shown as circular, the periphery of which extends slightly beyond the cylindrical cap 28 which is held in frictional engagement with the upper end of the barrel. The barrel may be provided with a chamber 29 for storing surplus leads, although this is not an essential feature of my invention.

For feeding the leads forward through the bore in the point 24, I prefer to employ a pusher-rod 30 arranged for longitudinal movement in the slot 21 and bore 23, said pusher-rod being provided with a rectangular head 31 arranged to fit snugly within said slot and provided on its outer edges with a rack arranged for engagement with the threads on the interior surface of the sleeve 26.

Secured to the top of the barrel by the screw 32 or other suitable means, is a plate spring 33 having a latch 34 designed to co-operate with the lower edge of the head 31 so as to hold the pusher-rod in the inclined position shown in Fig. 2, the upper edge of 105 said head being in such case held against the inclined lower surface of the top of the barrel.

Arranged for reciprocal movement in the barrel and cap is a plunger rod 35, the upper end of which projects through an aperture in the cap and the lower part, which is

square in section, through a hole in the upper end of the cap. The lower end of said plunger-rod is beveled as shown at 36 and is in contact with the inclined portion of 5 the spring 33, so that when the plunger-rod is depressed, the latch 34 will be moved laterally and the head of the pusher-rod released therefrom.

The peripheral surface of the head 27 of 10 the magazine will preferably carry indices denoting the character of the leads, such indices preferably being so arranged as to show the user the character of the lead in the compartment opposite the slot 21. The 15 cap may be provided with the usual pocket clip 37.

One operation is as follows:—

The magazine head is rotated to the proper point to bring the compartment carrying the desired lead into register with the slot 21, whereupon the lead 38 will drop through the slot and into the bore 23. The plunger-rod 35 is then depressed to release the pusher-rod which descends through the 25 slot until the racked head 31 is in engagement with the threads of the sleeve 26, whereupon rotation of the latter will cause the pusher-rod to move downwardly and feed the lead through the bore 23 as desired.

Should it be desired to employ lead of another color or grade before the lead in the bore 23 has been used up, the sleeve is rotated in the opposite sense until the racked head 31 is out of engagement with the 35 threads of the sleeve, whereupon the pencil is inverted, the plunger-rod depressed to move the latch 34 out of the path of the pusher-rod head, the plunger rod released so that the spring 33 will latch the head in 40 normal inoperative position, and then the pencil held horizontally with the magazine downward so that the lead 38 will again be received in its slot and the magazine rotated until the compartment containing the desired lead is in register with the slot 21, whereupon the operation of disengaging the 45 pusher-rod and feeding the lead forward, as above described, is repeated.

Having described an illustrative embodiment of my invention without however limiting the same thereto, what I claim and desire to secure by Letters Patent is:—

1. An automatic pencil comprising in combination a barrel having a transverse slot,

a magazine for leads rotatably mounted in 55 said barrel, a point secured to one end of said pencil, said point being provided with an axial bore communicating with said slot, a cap engaging the other end of said pencil, a pusher-rod provided with a rectangular 60 head, said pusher-rod being arranged for longitudinal movement in said slot and bore, and an interiorly threaded sleeve rotatably mounted on said barrel, the head of said 65 pusher-rod being provided with a rack arranged for engagement with the threads on the interior surface of said sleeve.

2. An automatic pencil comprising in combination a barrel having a transverse slot, a magazine for leads rotatably mounted 70 in said barrel, a point secured to one end of said pencil, said point being provided with an axial bore communicating with said slot, a cap engaging the other end of said pencil, a pusher-rod provided with a rectangular head, said pusher-rod being arranged for longitudinal movement in said slot and bore, a spring-latch for holding the pusher-rod in inoperative position, a 75 plunger-rod projecting through said cap for actuating said spring-latch, and an interiorly threaded sleeve rotatably mounted on said barrel, the head of said pusher-rod being provided with a rack arranged for engagement with the threads on the interior 80 surface of said sleeve.

3. An automatic pencil comprising in combination a barrel having a transverse slot, a magazine for leads rotatably mounted 90 in said barrel, a point secured to one end of said pencil, said point being provided with an axial bore communicating with said slot, a cap engaging the other end of said pencil, said magazine having a head the peripheral surface of which projects beyond the cylindrical wall of said cap, a pusher-rod provided with a rectangular head, said pusher-rod being arranged for longitudinal movement in said slot and bore, and an interiorly 95 threaded sleeve rotatably mounted on said barrel, the head of said pusher-rod being provided with a rack arranged for engagement with the threads on the interior surface of said sleeve.

In testimony whereof, I have hereunto 105 subscribed my name this 1st day of October, 1924.

ALBERT DAVOUST.
